C. J. DILL,
NECKTIE,
APPLICATION FILED FEB. 23, 1917.

1,267,387.

Patented May 28, 1918.

Cyril J. Dill

Inventor

By *Geo. P. Kimmel*

Attorney

UNITED STATES PATENT OFFICE.

CYRIL J. DILL, OF BURRWOOD, LOUISIANA.

NECKTIE.

1,267,387.

Specification of Letters Patent. Patented May 28, 1918.

Application filed February 23, 1917. Serial No. 150,563.

To all whom it may concern:

Be it known that I, CYRIL J. DILL, a citizen of the United States, and resident of Burrwood, in the parish of Plaquemines and State of Louisiana, have invented certain new and useful Improvements in Neckties, of which the following is a specification.

This invention relates to new and useful improvements in neckties, and the primary object of the invention is to provide a necktie of this character whereby the same when once tied may be held in position or positions, when applied to, or taken from a collar, thereby preventing the shape of the tie from being ruined by constant tying of the knot therein.

Another object of the invention is to provide a necktie of this character which is formed of two pieces, that are so tied, that one of the pieces has a projecting end portion that forms a neck band adapted to surround a collar, and detachably connected with the other piece, whereby when the two pieces are tied in a knot, the original knot may be retained therein during the removal or replacing the tie on a collar.

A further object of the invention is to provide a device of this character which is easily and simply constructed, inexpensive to manufacture, and one which will be very efficient in operation.

With these and numerous other objects in view my invention consists of the novel features of construction, combination and arrangement of parts which will be herein referred to and more particularly pointed out in the specification and claims.

In the accompanying drawing:

Figure 1 is a perspective view showing my new and improved type of necktie applied to a collar, and

Fig. 2 is a detail view showing the type of connection used between the two pieces of the necktie.

In describing my invention I shall refer to the drawing in which similar reference characters designate like and corresponding parts throughout the several views. In Fig. 1 of the drawing I have shown my new and improved type of necktie applied to a collar 1, which is of the conventional turn down type, but this type of tie is equally applicable to standing collars, etc.

The necktie comprises two unequal length sections, the longer section being designated

by the numeral 3, and the shorter section 2, that are adapted to be tied in any desired type of knot, preferably a four-in-hand as shown in the accompanying drawing, the two sections being so tied that the longest piece 60 3 is crossed intermediate its ends, while the short piece 2 is tied adjacent its upper end. This manner of tying the tie will leave two projecting ends, the end of the long section 3 being designated by the numeral 4 and of 65 the short section 3 is designated by the numeral 5. The projecting end portion 4 is adapted to form a neck band that surrounds the collar.

The free end of the neck band 4 has fastened thereto by stitching or any other desired means, and preferably within the tie as shown in Fig. 2 of the drawing, a hook member 6, while secured to the free end of the section 5 is a hook engaging loop 7, that 70 is adapted to detachably engage said hook.

In operation when it is desired to use this type of necktie, the two sections 2 and 3 are tied in any desired form of knot as has been hereinbefore described, and to place the same 80 on the type of collar as illustrated in the accompanying drawing, the hook member 6 has its lower portion engaging one edge of the downturned portion of the collar, and the neck band is then placed around between the 85 said downturned portion, and inner side of the collar, whereupon it is obvious that the loop 7 on the projecting end 5 of the shorter section on the necktie will be disposed adjacent the hook member 6 at the front of 90 said collar. The collar is then positioned around the wearer's neck, and when the two ends thereof are fastened, the loop 7 is operatively engaged with the hook 6, thereby connecting the adjacent ends of the neck 95 band and tie to securely hold the tie in position, and the knot may be then adjusted to the center of the same.

The use of this type of necktie, enables the tie to be originally formed with one type of 100 knot, and the said knot retained in its first position during the attachment and removal of the necktie to a collar. This obviates the constant wear and tear incidental to the placing and tying of the conventional type 105 of necktie every time the same is used. This type of necktie is easily and quickly adjusted to any desired kind of collar and its extreme simplicity of construction enables the same to be very economically manufactured.

From the foregoing description of the construction and operation of this new and improved type of necktie, the manner of applying the same to use and the operation thereof will be readily understood, and it will be seen that I have provided a simple and efficient means for carrying out the objects of this invention.

Having fully described my invention, what I claim as new, and desire to secure by Letters Patent, is:

1. A new article of manufacture including a necktie formed of two sections, one section having a portion thereof adapted to extend around a collar, a hook formed on the free end thereof, and a loop on one end of the

other section adapted to be engaged by said hook.

2. The combination with a collar, of a necktie formed in two sections adapted to be tied intermediate the ends of one section and adjacent one end of the other section, the projecting long end of said necktie extending around the collar to a point adjacent the front thereof, a hook formed on the free end of said section, and a loop formed on the projecting short end of said necktie and adapted for engagement with the hook to secure the necktie on a collar.

In testimony whereof, I affix my signature hereto.

CYRIL J. DILL.
